DESIGN FOR A CLOSURE OR SIMILAR ARTICLE

Benjamin Sidney Nash, Short Hills, N. J., assignor to Anchor Cap & Closure Corporation, Long Island City, N. Y., a corporation of New York

Application October 9, 1940, Serial No. 95,709

Term of patent 14 years

To all whom it may concern:

Be it known that I, Benjamin Sidney Nash, a citizen of the United States, residing in Short Hills, county of Essex, State of New Jersey, have invented a new, original, and ornamental Design for a Closure or Similar Article, of which the following is a specification, reference being had to the accompanying drawing forming a part thereof.

Fig. 1 is a top plan view of a closure showing my new design; and

Fig. 2 is an elevational view of the closure illustrated in Fig. 1.

I claim:

The ornamental design for a closure or similar article, substantially as shown.

BENJAMIN SIDNEY NASH.
